G. C. NELSON

VACUUM FEED SYSTEM

Filed May 13, 1921

Inventor:
Gustav C. Nelson
By: Wm. F. Belknap

UNITED STATES PATENT OFFICE.

GUSTAVE C. NELSON, OF MOLINE, ILLINOIS, ASSIGNOR TO THE BORG & BECK COMPANY, OF MOLINE, ILLINOIS, A CORPORATION OF ILLINOIS.

VACUUM FEED SYSTEM.

Application filed May 13, 1921. Serial No. 469,360.

This invention relates to liquid fuel systems for explosive engines and it is particularly useful as an accessory to an automobile or truck engine.

5 The primary object of the invention is to provide means of simple and substantial construction, and comprising comparatively few parts, for connection with the fuel supply tank and the intake manifold of the engine 10 whereby a constant and regular gravity fuel feed to the engine will always be maintained.

Another object of the invention is to provide an improved and sensitively operating means for quickly and alternately opening 15 and closing the vacuum producing connection and the air vent of a liquid fuel receiving chamber so that a constant and ample supply of fuel will always be maintained for the engine.

20 In the accompanying drawing I have illustrated, partly in section, a selected embodiment of the invention and referring thereto 1 is the receiving tank having a chamber 2, and 3 is a feed tank having a chamber 4, 25 these tanks being connected by a pipe 5 which is provided with a valve chamber 6, a valve 7 and a screen 8. The feed chamber is much larger than the receiving chamber and the construction is such that the two tanks may 30 be located in any desirable positions and the feed tank may be made in any desired size, shape and form. The receiving tank is provided with a head 9 which is secured in place on the tank by a rod 10 which projects

35 through the bottom of the tank and is threaded to receive a nut 11. An arm 12 on the inner side of the head 9 is provided with a nozzle end 13 and a passage 14 extending through the arm leads to a connection 15

40 which is connected by pipe (not shown) with the intake manifold of the engine. A similar arm 16 on the head 9 has a nozzle end 17 and a passage 18 extending through the arm leads to a vent pipe 19. A sleeve 20 has a

45 loose working fit upon the guide rod 10 and carries a float 21 and a cut-off for the nozzle 13 and the nozzle 17, this cut-off comprising the disk 22 and the disk 23 connected by collar 24 which is rigidly mounted on the sleeve 20.

50 The cut-off may be made in one piece or of several pieces, rigidly secured together. The nozzle 13 and the nozzle 17 are oppositely directed, in the form shown, the nozzle 13 being directed downwardly to be engaged by the disk 22 and the nozzle 17 being directed

upwardly to be engaged by the disk 23 and these nozzles and disks are so located with relation to each other and so constructed that a very little movement of the float is sufficient to seat the disk 22 on the nozzle 13 or 60 the disk 23 on the nozzle 17 whereby the cut-off alternately opens and closes the vacuum connection and the air vent. The double cut-off disk revolves with the float upon the guide rod 10 in the actual use of the apparatus, 65 thereby keeping itself clean, and this movement is increased by arranging the discharge end 25 of the liquid fuel supply inlet 26 so that it will discharge upon the top of the float. 70

My invention provides a substantial but simple and compact structure which will operate sensitively and efficiently under all usual conditions of road travel when the apparatus is installed in an automobile or in 75 a truck to supply a constant and sufficient fuel feed to the engine at all times.

My improved double disk cut-off and the parts immediately associated therewith may 80 be embodied in a vacuum feed system constructed differently from that shown in the accompanying drawing and it will be understood, therefore, that I do not limit myself to this particular embodiment but I reserve the right to make all such changes, adaptations and installations as fairly fall within 85 the scope of the following claims.

I claim:

1. In a vacuum feed system, a tank having a receiving chamber, a vacuum connection to said receiving chamber terminating in a vertically directed nozzle, an air vent for the receiving chamber terminating in a vertically directed nozzle, a pair of cut-off disks disposed to control said nozzles, and a revolvably mounted float rigidly secured to the disks and adapted to operate the disks to open and close the vacuum connection and the air vent alternately. 90

2. In a vacuum feed system, a tank having a receiving chamber, a vacuum connection to said receiving chamber, an air vent for the receiving chamber, said vacuum connection and air vent having oppositely disposed nozzles, a pair of operatively connected disks disposed on opposite sides of said nozzles, and a slidably journaled float rigidly secured to one of said disks for operating said disks to alternately open and close the vacuum connection and the air vent. 100

3. In a vacuum feed system, a tank having a receiving chamber, the vacuum producing connection to said receiving chamber having a downwardly-directed nozzle, an air vent for the receiving chamber having an upwardly directed nozzle, a pair of connected revoluble cut-off disks disposed on opposite sides of said nozzles, and a float rigidly secured to one of said cut-off disks for operating said cut-off disks to alternately seat against said nozzles for opening and closing the vacuum connection and the air vent.
4. In a vacuum feed system, a tank having a receiving chamber, a valve in said chamber comprising two parallel disks spaced apart, a fuel supply inlet discharging into said chamber, a vacuum producing connection and an air inlet terminating in nozzles in said chamber arranged between said disks, and a float controlling said disks for closing said nozzles.
5. In a vacuum feed system, a tank having a receiving chamber, a float in said chamber, a pair of disks carried by said float and spaced apart, an air vent for said chamber terminating in a nozzle lying between said disks and adapted to be closed by one of them, and a vacuum producing connection to said receiving chamber and terminating in a nozzle between said disks and adapted to be closed by the other one thereof.
6. In a vacuum feed system, a tank having a receiving chamber, a float in said chamber, a pair of disks carried by said float and spaced apart, a collar connecting said disks, an air vent for said chamber terminating in a nozzle lying between said disks and adapted to be closed by one of them, a vacuum producing connection to said receiving chamber and terminating in a nozzle between said disks and adapted to be closed by the other one thereof, and a fuel supply inlet terminating in a discharge within said chamber.

GUSTAVE C. NELSON.
